US0D1088463S

(12) **United States Design Patent** (10) **Patent No.:** **US D1,088,463 S**
(45) **Date of Patent:** **** Aug. 19, 2025**

(54) **INSOLE**

(71) Applicant: **Fuzhou Winggood Technology Co., Ltd.**, Fuzhou (CN)

(72) Inventor: **Jingyu Liu**, Linying (CN)

(73) Assignee: **Fuzhou Winggood Technology Co., Ltd.**, Fuzhou (CN)

(**) Term: **15 Years**

(21) Appl. No.: **29/932,291**

(22) Filed: **Mar. 13, 2024**

(30) **Foreign Application Priority Data**

Sep. 15, 2023 (CN) 202330601194.0

(51) **LOC (15) Cl.** **02-04**

(57)

CLAIM

The ornamental design for an insole as shown and described.

DESCRIPTION

FIG. 1 is a top perspective view of an insole showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom perspective view thereof.

1 Claim, 6 Drawing Sheets
